UNITED STATES PATENT OFFICE.

JOHN GIBBONS, OF WEST TROY, NEW YORK, ASSIGNOR TO THE UNION HARD-WARE MANUFACTURING COMPANY, OF SAME PLACE.

SNAP-HOOK.

SPECIFICATION forming part of Letters Patent No. 292,164, dated January 22, 1884.

Application filed October 9, 1883. (No model.)

To all whom it may concern:

Be it known that I, JOHN GIBBONS, of the village of West Troy, county of Albany, and State of New York, have invented a new and useful Improvement in Harness Snap-Hooks, of which the following is a specification.

My invention relates to snap-hooks, a class of devices that are used to make harness-connections, and which are generally made with a hook having an eye or link form opening at its shank end for attachment, and a latch that is hinged to the shank and forced to engage with the point of the hook by means of a spring.

My invention consists, as will hereinafter be fully detailed in the specification and claim, of an improvement in the construction of the hinging attachment by which the latch attaches to the hook-shank.

Accompanying this specification, and forming a part of it, is a sheet of drawings containing five figures illustrating my invention and improvement, with the same designation of parts by letter-reference used in all of them, of which—

Figure 1 shows a plan view of a snap-hook with the latch detached therefrom, and shown as an annex, A. Fig. 2 illustrates a top view of a snap-hook and connected latch; Fig. 3, a view of the under surface of the separated parts of the device turned toward the right, with the intermediate spring omitted, the latch thus illustrated indicated as the annex figure B. Fig. 4 shows a side elevation of the device, with the latch forced down against the spring; and Fig. 5 is another side elevation of the device, with the latch forced to engage with the hook by the spring.

The several parts of the device are designated by letter-reference, and their function is described as follows:

The letter S indicates the shank of the hook, and H the latter; E, an opening or eye for attachment, formed in the widened-out shank end; L, the latch, and D a helical spring.

The letter O' designates a sink formed in the under face of the latch to receive one end of the spring, and O² a sink made in the upper face of the hook-shank to receive the other end of the said spring.

The letter G indicates a guide-pin on the under surface of the latch, and N a passage-way for said pin through the shank, all of which parts, as thus before named, constitute the well-known construction of such devices.

As snap-hooks have heretofore been made the latches have been hinged to the shank by means of hinging-pins that were passed through ears on the shank, and a tonguing-piece on the latch, or by end straps on the latter that were bent around a hinging-pin on the shank, either of which methods required fitting. To improve upon these older methods is the object of my invention, and the better construction is produced by the following means:

The letters a a designate two rounded-out hinge-bearings made in the under surface of the shank S, and d d recesses formed in the edge of the opening E and adjacent to said bearings, and p a projecting pin arranged between said recesses and parallel to the bottom surface of said shank.

The letters b b indicate journal-pins projected from the sides of the latch at its hinging end, and adapted to enter said bearings in the shank.

The letter N indicates a recess formed on the end of the latch between the journal-pins, and adapted to receive the pin p on the shank when the parts are connected.

To connect the latch and hook-shank thus made, the end of the hook H (indicated at 1) is cast with an offset-bend, (designated by the dotted line I²), and which bend is straightened out after the latch has been inserted. To connect the latch and shank, the hinging end of the former is passed down through the opening E of the latter. The journal-pins b b on the latch are entered into the bearings a a in the shank, and the pin p on the latter within the recess N on the latch, by which a hinging interlocking mechanism is produced that requires no fitting for attachment, each factor of which can be made or cast with the part on which it is formed.

These devices, being made of malleable cast-ings, are adapted to be bent on the hook end to receive the latch, as stated, and then bent back to retain the latter in position.

Having thus described my invention, what I claim, and desire to secure by Letters Patent, is—

In a snap-hook, the combination of the hinging-pins *b b* and the intermediate recess, *N*, on the hinging end of the latch, the bearings *a a*, and the intermediate pin, *p*, on the hook-shank,

constructed to connect and operate as and for the purposes herein set forth.

JOHN GIBBONS.
